(57) **CLAIM**

We claim the ornamental design for a posture control brace, as shown and described.

DESCRIPTION

FIG. 1 is a front elevation view of a posture control brace showing our new design with a human form superimposed in dashed lines for illustrative purpose only and forms no part of the claimed design;

FIG. 2 is a front perspective view thereof;

FIG. 3 is a front elevation view shown in an alternative unfastened configuration with dashed lines for hook and loop fasteners thereof;

FIG. 4 is a front elevation view thereof; and,

FIG. 5 is a rear elevation view thereof.
